FIG. 1 is a top plan view of a cup or the like embodying our new design.

FIG. 2 is a side elevational view.

FIG. 3 is a rear elevational view.

FIG. 4 is a bottom plan view.

The essential feature of the design is characterized by the wall portions of the cup having a bulbously rounded convex bottom portion, a slightly concave and substantially linear central portion, and an arcuately-outwardly flared upper lip portion.

We claim:

The ornamental design for a cup or the like, as shown and described.
